US00D778966S

(12) **United States Design Patent** (10) **Patent No.:** **US D778,966 S**
(45) **Date of Patent:** **** Feb. 14, 2017**

(54) **SKIVING DEVICE**

- (71) Applicant: **Physical Optics Corporation**,
Torrance, CA (US)
- (72) Inventors: **David Harold Miller**, San Pedro, CA
(US); **Edward Matthew Patton**,
Torrance, CA (US)
- (73) Assignee: **Physical Optics Corporation**,
Torrance, CA (US)
- (**) Term: **14 Years**
- (21) Appl. No.: **29/510,727**
- (22) Filed: **Dec. 2, 2014**

CLAIM

The ornamental design for a skiving device, as shown and described.

DESCRIPTION

FIG. 1 is a perspective view of a skiving device;
FIG. 2 is a front elevational view of a skiving device;
FIG. 3 is a rear elevational view of a skiving device;
FIG. 4 is a side elevational view of a skiving device;
FIG. 5 is an opposite side elevational view of a skiving device;
FIG. 6 is a top plan view of a skiving device; and,
FIG. 7 is a bottom plan view of a skiving device.
The dashed lines of the projectile and/or components thereof
and unshaded areas within the dashed lines depict unclaimed
environmental subject matter.

1 Claim, 7 Drawing Sheets
